UNITED STATES PATENT OFFICE.

ROBERT NELSON FRAME, OF BUFFALO, NEW YORK.

BOOKMARKER.

1,338,861.

Specification of Letters Patent.

Patented May 4, 1920.

Application filed February 12, 1919. Serial No. 276,632.

To all whom it may concern:

Be it known that I, ROBERT NELSON FRAME, a citizen of the United States, residing at Buffalo, in the county of Erie and 5 State of New York, have invented new and useful Improvements in Bookmakers, of which the following is a specification.

This invention relates to a movable marker or indicator designed more particularly for use on the leaves of account books to facilitate reference to entries and guard against oversights, especially where the work of the bookkeeper or auditor is liable to interruptions.

15 The object of my invention is the provision of a convenient and inexpensive device of this character which can be readily shifted from line to line of an account or from place to place of a page, and which 20 at the same time is attached with sufficient security to prevent its accidental displacement.

In the accompanying drawings:

Figure 1 is a face view of the marker applied to the leaf of a ledger. Fig. 2 is a similar view of the device detached from the book. Fig. 3 is a longitudinal central section of the marker. Fig. 4 is a side or edge view thereof applied to a leaf which is 30 shown in section.

Similar characters of reference indicate corresponding parts throughout the several views.

The marker or indicator consists of a 35 plate 1, preferably of thin sheet metal, as spring steel, having the form of an arrow with a comparatively broad tail, as shown. This plate is of the proper length to extend from the outer, side edges of the book- 40 leaves to the amount-columns or to any other desired point.

The plate is adapted to lie flat upon the face of a leaf and is provided with a spring tongue 2 adapted to bear against the back of 45 the same or another leaf, as shown in Fig. 4, so as to clasp the marker to the leaf or leaves. This tongue is arranged lengthwise of the marker and extends inwardly from a point near its outer end, the same being of 50 suitable length to form an extensive holding surface. As shown, the tongue is stamped integral with the body of the marker by cutting a three-sided opening 3 of proper form therein. Through this opening the entries 55 in the underlying columns are displayed.

In the preferred embodiment of the device illustrated in the drawings, the root or attached end of the tongue is depressed below the plane of the marker-plate by providing the tongue at that point with an offset or 60 shoulder 4 arranged on the rear side of the plate. This construction permits the tongue to receive and embrace either one or several leaves and yet allow it and the plate to bear substantially flat against the leaves. The free 65 end of the tongue may be curved away from the plate, as shown at 5, to form a flaring mouth between these parts which facilitates the application of the marker to the leaves.

If desired, the marker may be provided 70 with an opening 6 for suspending it from a hook or other support.

In the use of the device, the same is simply slipped over the edge of the leaf to be marked, with its shoulder 4 abutting against 75 the edge of the leaf, and as the work progresses, the marker is shifted over the page, its projecting tail affording a convenient handle for this purpose.

Both the face or indicator plate 1 and 80 the tongue 2 are flat and smooth and free from projections of any kind and the device is therefore not liable to wrinkle the leaves of a book, or tear them in applying and removing it.

85 While the improvement is herein shown in connection with an account book, it is equally serviceable for other books of various kinds, such for example, as stenographers' notebooks, and also for manuscripts 90 and various other papers.

I claim as my invention:

A book marker, comprising an indicator- 95 plate of resilient material adapted to lie upon the face of a leaf, said plate being provided at its front end with a pointer and in rear thereof with a three-sided opening through which subjacent entries on said leaf are exposed, and a spring-tongue integral with said plate and formed by the 100 cutting of said opening, said tongue terminating short of said pointer and its attached end being provided at its junction with the plate with an offset arranged on the rear side of the plate, whereby the tongue is depressed rearwardly out of the plane of the plate, all portions of said plate being flat, smooth and free from projections and lying in the same plane except said tongue.

ROBERT NELSON FRAME.
